UNITED STATES PATENT OFFICE.

ALBERT S. TRASK, OF CONCORD, NEW HAMPSHIRE.

DESIGN FOR A COMBINED LAMP AND BOOKRACK.

Application filed September 8, 1922. Serial No. 3,654. Term of patent $3\frac{1}{2}$ years.

To all whom it may concern:

Be it known that I, ALBERT S. TRASK, a citizen of the United States, residing at Concord, in the county of Merrimack, State of New Hampshire, have invented a new, original, and ornamental Design for Combined Lamp and Bookrack, of which the following is a specification, reference being had to the accompanying drawing, forming part thereof.

The figure is a perspective view of a combined lamp and book rack, showing my new design.

I claim:

The ornamental design for a combined lamp and book rack, as shown.

ALBERT S. TRASK.
